STRAP FASTENING TOOL

Michael J. McAneney, Hillsboro, N. Mex.

Application June 19, 1944, Serial No. 541,102

7 Claims. (Cl. 81—9.1)

1

My present invention relates to a tool for tying, drawing, or fastening straps, or the like, to or around various objects or articles, and also to a combination of such a tool and strap fastening means.

One of the principal objects of this invention is to provide a tool of this class which may be used with equal effectiveness for all purposes of tying, drawing, tightening or fastening of straps around various articles, such as in hose clamping or banding; box strapping; bale tying, and the like, and one which may be also used in fastening straps of various widths, various gauge materials, as well as straps of different materials.

Another important object of this invention is to provide a tool of this class for taking up considerable lengths of the tying strap during a single stroke of the operation of the tool, and also a tool of this class whereby considerable leverage may be exerted in tying the strap at or near the end of the strap tightening operation, it being an object of this invention to provide either one or the other or both of such methods of strap take-up.

An important object of this invention also is to provide a tool of this class whereby the strap, band, or the like, may be bent over or upon itself, or over the tie buckle without rotating or substantially moving the tool.

An important associated object is the provision of a tool of this class whereby no tension or other strain is applied on the band or strap other than that of bending the same, as before mentioned.

A further important object of this invention is to provide a tool of this class in which the band or strap, when drawn tightly, may be temporarily clamped or secured in such drawn condition, while bending the end thereof upon itself or over the tie buckle, or when adjusting the tool for another bite for further tightening the band or strap.

A still further important object of this invention is to provide a tool of this class which is relatively small and light of weight so that it is readily portable and may be readily carried, used at arm's length or overhead, and other places where lightness of weight and small size are essential.

Still another important object of this invention is to provide simple and efficient means of holding the buckle which is adapted to secure the ends of the strap together, it being an important object also to provide a buckle holding means of this class in combination with means for temporarily holding the strap in a tightly drawn condition

2

while either again gripping the strap for another bite or further take-up operation or for fastening or securing the free end of the strap to the buckle.

It is a further important object of this invention to provide novel and simple means for gripping the end of the strap or band to be drawn or tightened with respect to the buckle, and also simple and effective means for drawing such end quickly and also with considerable force, and further to provide such means in a compact sliding member and in combination with means for cutting the strap or band.

An important object also of this invention is to provide a novel combination of a strap, buckle therefor, and a tool for holding the buckle and tightening and fastening the strap with respect to the buckle.

An important modification of my invention is to provide a tool of this class which may be readily placed astride a strap and buckle from the side of the strap and particularly when the loose end of the strap extends a considerable distance beyond the buckle, or when the strap is uncut.

With these and other objects in view, as will appear hereinafter, I have devised a strap fastening tool, and combination thereof with a buckle and strap, having certain novel features of construction and arrangement of parts and portions, as will be hereinafter described in detail and particularly set forth in the appended claims, reference being had to the accompanying drawings, and to the characters of reference thereon, which form a part of this application, in which:

Fig. 1 is a plan view of my strap fastening tool in a preferred form, the dotted lines showing another arrangement of means for operating the tool;

Fig. 2 is a side elevational view thereof, the tightening jaws and the strap bending die being shown by dotted lines in certain shifted positions;

Figs. 3 and 4 are, respectively, transverse sectional views thereof, taken through 3—3 and 4—4 of Fig. 2;

Fig. 5 is an enlarged fragmentary longitudinal sectional view taken through 5—5 of Fig. 1, showing the construction of the head of the tool, and in a position before the buckle is clamped into place, and with the strap bending die shifted to a remote position;

Fig. 6 is a similar longitudinal sectional view of the head but showing a buckle clamped by the tool and the normally free end of the strap in a clamped position, and with a strap bending die

in a forward strap-bending position, portions being broken away and in section to facilitate the illustration;

Fig. 7 is an enlarged fragmentary elevation taken at 7-7 of Fig. 1, showing the jaw means for gripping the free end of the strap for drawing the same tightly around the object to be tied, bound, or clamped, showing one means by solid lines and another by dotted lines for moving or operating the same, and also showing the means for cutting the strap;

Fig. 8 is an enlarged transverse sectional view, taken through 8-8 of Fig. 7, showing particularly the slide for carrying the jaw means and the cutter;

Fig. 9 is a fragmentary view of the slide, in plan, taken through 9-9 of Fig. 8, and showing additionally the means of locking the slide to the feed screw;

Fig. 10 is a longitudinal section of the latter portion, taken through 10-10 of Fig. 9;

(Figs. 9 and 10 show fragmentarily and by solid and dotted lines different means of operating the same, the operating means being shown the reverse from those shown in Figs. 1, 2, and 7);

Fig. 11 is a rear view of the end portion of the device, taken at 11-11 of Fig. 7;

Fig. 12 is a perspective view of a strap and buckle adapted to be used in my fastening tool; and,

Fig. 13 is a perspective view of a modified form of the head whereby the tool may be placed astride or secured to the buckle and strap from the side of the latter.

One form of strap fastening means with which the tool of my present invention is adapted to be used is that shown in my co-pending application, Serial No. 537,407, filed May 26, 1944, now issued as Patent No. 2,533,275, dated December 12, 1950. This strap fastening means consists of a buckle A and a strap or band B, one end designated B¹, of the latter being fastened to the buckle, the intermediate portion thereof, designated B², being looped around the object or article to be clamped or bound by the strap, and the free end B³ thereof being adapted to be threaded and drawn through the buckle, tightly around the article to be clamped or bound, and bent over or fastened to the buckle after being so drawn tightly around the object or article.

The essential parts of my invention consist of a head C and a movable member D, the latter containing the take-up jaw means, cutter, and the like.

The head C consists of a head member 1 which is bifurcated at its forward end providing furcations 1^a. These furcations have transverse recesses 1^b at their undersides and near their forward end, these recesses forming pockets 1^c at the rear edges of the recesses 1^b for receiving one edge of the buckle A. The normally outer side or outer plate portion of the buckle engages the bottom of the recess 1^b. The other or forward edge of the buckle is engaged by a movable jaw 2^a provided adjacent the lower and rear sides of a slide 2 which is reciprocally mounted on ways 1^d at the adjacent sides of the furcations 1^a. The slide is held in position by an angular retaining plate 3 extending between and over the outer ends of the furcations of the head member 1.

The slide 2 is moved backwardly into buckle-engaging position by means of an eccentric 4 which is carried on a pin 5, this pin being rotatably mounted between the furcations 1^a. The eccentric is positioned in vertically elongated slots

2^b in the end or leg portions 2^c of the slide, which is U-shaped, the leg portions being mounted on the ways 1^d. At one end of the pin 5 is provided a lever 6 which, when shifted from the position shown in Fig. 5 to the position shown in Fig. 6, is adapted to move the slide 2 to the buckle engaging position shown in Fig. 6.

From this buckle, the end B¹ of the strap B may extend under the tool, thence around the article or object to be clamped, and is then threaded with its other end B³ through the normally forward edge of the buckle.

On the eccentric 4 is pivotally mounted a dog 7 which is provided at its free ends with teeth 7^a

15 which are adapted to engage the upper side of the end B³ of the strap, and clamp the strap against the buckle or against the end B¹ of the strap. The free end of the dog is adapted to extend between clamping ears A¹ of the buckle A.

20 On the hub portion of the dog is provided a slot 7^b in which is located a stop in the form of a screw 8, which is secured to the eccentric 4. This slot 7^b permits limited movement of the dog about the eccentric, the screw 8 limiting such pivotal movement.

25 As the lever 6 is shifted to the position shown in Fig. 6, the dog 7 is forced against the strap B and locked in position by the eccentric. Thus, the strap may be simultaneously held in position with the clamping of the buckle by 30 the head, but the dog alone may be loosened slightly to permit the strap to be drawn freely through the buckle.

Intermediate the forward and rear ends of the head member 1 are provided spaced shoulders 1^e into which are screwed guide rods 11, these guide rods extending backwardly and upwardly, the rear ends of the guide rods being positioned considerably above the plane of the base of the head member. The rear ends of the guide rods are secured relative to each other by means of an end member 12, the same being secured to the rods by screws 13.

On the guide rods is slidably mounted an operating or jaw carrying slide 14. This slide has a slot 14^a extending from the front to the rear end and open at one side, as shown best in Figs. 7, 8, and 10. The free end B³ of the strap is adapted to extend backwardly through this slot. The slide 14 is provided in the rear portion with a recess 50 14^b in which is positioned a jaw support 15, which is secured in position by a screw 15^a. This support 15 carries a dog 16. The dog is pivotally mounted at its forward end on the support 15, and has a notched free end 16^a which extends

55 into the slot 14^a from the upper side thereof, the free end of the dog being forced into said slot by a spring 17. Thus, the free end B³ of the strap is automatically secured within the slot 14^a when placed therein.

60 In order to permit extreme forward movement of the slide 14 the head member is undercut at 1^h backwardly from the faces 1^e, this undercut portion or depression 1^h extending to near the bottom of the member 1. The bottom of the depression may be inclined at the angle of the guide rods 11. This construction permits the slide 14 to be shifted so that the forward end may engage the faces 1^e.

The operating or jaw carrying slide 14 is moved 70 or drawn backwardly on the guide rods 11 in order to draw the free end of the strap through the buckle and tightly around the object or article to be tied or clamped. One means for drawing the slide 14 backwardly consists of a lever 21 and a link 22, the former of which is

detachably mounted with one end on a rotating pivot 23 located at one side of the end member 12. The intermediate portion of the lever 21 is pivotally connected by the link 22 to the side of the slide 14. Thus, when the free end of the lever 21 is drawn backwardly, the slide is moved backwardly on the guide rods 11.

This method of moving backwardly the slide 14 and of taking up the slack in the strap B, from the end B³ thereof, may take up as much as three or four inches, or more, of the length of the strap during one stroke of the lever 21. This construction and method of operation is sufficient for box strapping or bale tying. It is obvious, however, that great tension cannot be exerted on the strap B by this method, such as is or may be required in hose clamping, and the like, except for the initial take-up. In order to draw the strap more tightly, I have provided a feed or take-up screw 31 which is positioned between the guide rods 11 and is mounted at one end portion of the end member 12. It is fixed against longitudinal movement with respect to the end member by a flange 31^a on the screw and by a collar 32 secured to the screw in front of the end member. The screw is provided with a square rear end 31^b for receiving the lever 21.

The screw extends through the operating or jaw carrying slide 14 and is operatively connected thereto by means of a pair of nut members 33 at the opposite sides of the screw, the nut members together forming a split nut. These nut members 33 are provided with angularly positioned and upwardly extending lugs 33^a which extend into angularly positioned slots 34^a in the split nut operating member 34. The portions of the member 34 in which the slots 34^a are provided are slidably arranged between the main portion of the slide 14 and a cover 14^c, as shown best in Figs. 9 and 10, the cover being secured in place by screws 14^d.

The split nut operating member 34 is moved longitudinally of the screw by a lever mechanism which consists of a lever 35 which is pivoted at one end on a lug 14^e extending upwardly from the rear end of the cover 14^c, and a link 36 pivotally connecting an upwardly extending lug 34^b on the member 34 to the intermediate portion of the lever 35. When the lever 35 is shifted to its solid line position, shown in Figs. 1, 2, and 7 of the drawings, the member 34 is shifted and locked in its forward position, causing the nut members 33 to be contracted relative to each other and to engage the opposite sides of the screw 31, thus permitting the slide 14 to be moved by the rotation of the screw 31.

The same lever 21 is adapted for rotating the screw, but in this instance the ratchet portion at the hub end of the lever 21 is utilized to permit rapid rotation of the screw 31 by mere oscillation of the lever. This ratchet means consists of a ratchet wheel 21^a, which is fitted directly over the square portion 31^b of the screw, and a pawl 21^b pivotally mounted within a recess in the enlarged portion 21^c of the lever 21.

The operating or jaw carrying slide 14 may be manually returned, if required, to its forward position, by opening the split nut, for another bite upon the end B³ of the strap. In order to disconnect the slide 14 from the screw 31, the lever 35 is raised, which disengages the nut member 33 from the screw 31, and the lever 35 is again depressed when the slide 14 is in its forward position.

At the forward portion of the slide 14 is pro-

vided a rotary cutter 41. This cutter is mounted in a transverse bore 14^f at the forward portion of the slide, this bore straddling the longitudinal slot 14^a. The cutter, shown best in Figs. 7, 9, and 10, consists of a segmental cutting portion 41^a extending from one end of a cylindrical portion 41^b. From the cylindrical portion extends a boss 41^c to which is secured a handle 42, for rotating the cutter and causing one of the edges thereof to move across the slot 14^a through which the end B³ of the strap extends, thus cutting the strap to the length desired.

The arm 42 for the cutter is intended to be rotated in the direction of the arrow shown in Fig. 7, thereby shearing the strap at the forward side of the bore 14^f. The slide 14 is provided with a clearance in the form of a channel 14^g, shown best in Figs. 7, 9, and 10, to permit the severed end B³ of the strap to spring upwardly.

The portion of the end B³ of the strap which is drawn through the buckle A extends over a die member 51. This die member has guides 51^a which are slidably mounted in grooves 1^f at the opposite sides of a longitudinal channel 1^g in the head member 1, the grooves extending from the rear end of said head member to the rear end of the forward furcations 1^a. This die has a curved recess 51^b at its forward end, which recess is formed by a downwardly and rearwardly inclined edge 51^c. As this die member is moved forwardly, it engages the free end B³ of the strap and forces the same forwardly over the upper plate portion of the buckle A and between the spaced apart ears 1^d, which extend upwardly from the buckle. The initial forward movement of the die 51 is effected by a rod 52 which extends beyond one side of the head member 51. This rod 52 also forms the carrying support for a roller 53 which is positioned within a recess 51^d at the rear portion of the die. This roller is adapted to be engaged by the lower portion of the forward end of the slide 14 to facilitate the bending of the end B³ over the buckle, as shown by dotted lines in Fig. 2. The slide 14 may be moved forwardly for such purpose by either the lever 21 and link 22, or by means of the screw 31.

In the modified construction of the head, shown in Fig. 13, the head is open at one side to permit a long free end or portion B³ of the strap, which is already threaded through the buckle, or an end which is threaded through the buckle wound on a roll, to be inserted into the head from the side, so that it may be secured to the jaw means carried by the slide 14. In this modified structure, the head is preferably made of two or three members, the drawing showing three separate members, namely, a main head member 61, forming the main support and one side, a side member 62 forming the opposite side, and a cantilever member 63, which may be secured to the ends of the members 61 and 62 by screws 64. The slide 2 is slidably mounted between the members 61 and 62, as in the former construction. One guide rod 11 extends backwardly from a shoulder 61^a of the member 61 and the other rod from a corresponding shoulder of the member 62. A space or passage E is provided between the rear end of the side member 62 and the adjacent portion of the member 61, whereby the portion of the strap, secured to the buckle, may be readily placed in alignment with the jaw means of the slide 14.

Before securing the strap fastener around a hose, box, or the like, one end of the strap or band B is secured to the buckle A. The buckle

A is then inserted in the recess 1^b of the head member 1 and secured or locked therein by moving the slide 2, thereby clamping the buckle between the fixed jaw 1^c of the movable jaw 2^a. The strap or band is then drawn around the object to be clamped with the band extending backwardly underneath the tool and around the object. The free end B² of the band or strap is then drawn through the front end of the tool and threaded through the buckle, immediately over the end B¹ secured to the buckle, and below the upper fold of the buckle between the clamping ears A¹. The extended end of the band or strap is then threaded through the horizontal slot 14^a of the slide 14. This may be done by inserting the portion B³ into the side of the slot. The pawl 16 rests upon the portion B³ of the strap or band, and when the slide 14 is drawn backwardly by either the lever 21 and link 22, or by means of the screw 31, the band or strap is drawn through the buckle tightly around the object to be clamped. The pawl 7 on the slide 2 resting upon the portion B³ of the strap automatically grips and retains the free end of the strap in the aforementioned position and holds the same while the slide 14 is moved forwardly for another bite upon the strap in order more tightly to draw it around the object. When the strap is drawn sufficiently tight, it may be cut by the cutter 41. The slide 14 is then drawn backwardly while the die 51 is forced forwardly. The slide 14 is then moved forwardly into engagement with the die 51 which causes the end B³ of the strap to be folded over the buckle between the ears A' of the buckle, the forward downwardly and rearwardly inclined edge of the die engaging underneath the end of the strap and, in forward movement of the die over the upper surface of the buckle, folding the strap end over the buckle and between the ears. The forward or lateral portion of the die defined by the curved recess therein serve to engage the ears of the buckle to produce at least a partial inward folding of the ears. The die is then returned to its rear position and the buckle with the strap end bent thereover is released by moving slide 2 forwardly and thereby opening jaws 1^c and 2^a.

Though I have shown and described a particular construction, combination, and arrangement of parts and portions, and a certain modification thereof, I do not wish to be limited to the same, but desire to include in the scope of my invention the construction, combination, and arrangement substantially as set forth in the appended claims.

I claim:

1. In a means of the class described, the combination with a strap having a buckle secured at one end thereof and provided with means for receiving and securing another portion of the strap, the other end of the strap being securable to said buckle by said means, of a tightening tool having a jaw means for receiving and clamping the buckle, a second jaw means at one side of the first jaw means for gripping said other end of the strap, the second jaw means being movable on the tool for drawing said other end of the strap tightly with respect to the buckle, a dog at the opposite side of the first jaw means for gripping and holding said other end of the strap with respect to said buckle when said other end of the strap is released by the second jaw means, and means in association with the first jaw means for folding said other end over said buckle and securing said end thereto.

2. In a means of the class described, the combination with a strap having a buckle secured at one end thereof, the other end of the strap being threaded through and securable to said buckle, said buckle having ears extending at right angles from said buckle and at the opposite sides of said strap exposing said other end, of a tightening tool having a jaw means for receiving and holding the buckle, a second jaw means at one side of the first jaw means for gripping the other end of the strap, the second jaw means being movable on the tool for drawing said other end of the strap tightly through said buckle, a dog on the tool at the opposite side of the first jaw means for preventing withdrawal of said other end of the strap from said buckle, said dog engaging said other end of the strap between said ears, and means in association with the first jaw means for folding said other end over said buckle and securing said end thereto.
3. In a means of the class described, the combination with a strap having a buckle secured at one end thereof, the other end of the strap being securable to said buckle, of a tightening tool having a jaw means for receiving and holding the buckle, another jaw means for gripping said other end of the strap, the other jaw means being movable on the tool for drawing said other end of the strap tightly with respect to the buckle, a dog for gripping and holding said other end of the strap with respect to said buckle when said other end of the strap is released by the second jaw means, and a die on the tool in association with the first jaw means for bending said other end of the strap over the buckle when the same is gripped and held by said dog.
4. In a tool of the class described, a frame adapted to receive a strap, jaw means slidably mounted on the frame and adapted to grip a portion of the strap, means on the frame for moving directly the jaw means and means on the frame for clamping securely the strap intermediate its ends while the jaw means is released from the strap, said moving means being disconnectable from the jaw means, a screw on the frame positioned parallel to the path of the movement of the jaw means, and means readily detachably connecting the jaw means to the screw, whereby the jaw means may be moved by the operation of the screw or disconnected therefrom.
5. In a tool of the class described, a frame adapted to receive a strap, jaw means slidably mounted on the frame and adapted to grip said strap, a screw on the frame positioned parallel to the path of the movement of the jaw means and connected thereto, means on the frame for clamping and securing the strap intermediate its ends while the jaw means is released from the strap, and a slidably die movable in front of the jaw means on the frame and operable by the screw for bending the strap backwardly upon itself when the same is released by the jaw means.
6. In a tool of the class described, a frame adapted to receive a strap, jaw means slidably mounted on the frame and adapted to grip said strap, means on the frame for moving directly the jaw means on the frame, means for clamping securely the strap intermediate its ends while the jaw means is released from the strap, said moving means being disconnectable from the jaw means, a screw on the frame positioned parallel to the path of the movement of the jaw means, means readily detachably connecting the jaw means to the screw, whereby the jaw means may be moved by the operation of the screw or disconnectable from the jaw means.

nected therefrom, and a slidable die movable in front of the jaw means on the frame and operable either by the moving means or screw for bending the strap backwardly upon itself when the same is released by the jaw means.

7. Means as defined in claim 3 characterized by the dog gripping and holding said other end of the strap under tension with respect to the buckle with an untensioned end portion of the strap extending beyond the buckle to be engaged by the die for bending the untensioned end portion over the buckle while the strap is gripped and held under tension by the dog.
